G. R. STARK

ROOFING ELEMENT

Filed July 26, 1927

UNITED STATES PATENT OFFICE.

GERALD R. STARK, OF SOUND BEACH, CONNECTICUT, ASSIGNOR TO THE FLINTKOTE COMPANY, OF BOSTON, MASSACHUSETTS, A CORPORATION OF MASSACHUSETTS.

ROOFING ELEMENT.

Application filed July 26, 1927. Serial No. 208,454.

This invention relates to roofing elements, more particularly those formed of a flexible fibrous base impregnated and coated with suitable waterproofing material and surfaced with a layer of crushed slate or the like.

One of the objects of the invention is to provide an individual shingle element adapted to be laid widely spaced with similar elements in successive overlapping courses, and having a folded-under nailing tab proportioned so as to serve also as a gauge in properly and uniformly aligning and spacing the shingle elements of each course.

Another object of the invention resides in the provision of shingle elements having folded-under nailing tabs and being designed so that when the elements are in place in their assembled relation on the roof, the overlapping marginal edges of each element will lie flat and snug against the surface of the adjacent underlying shingles, whereby to reduce to a minimum the tendency for wind and rain to drive sidewise under said edges, and into contact with the roof supporting structure.

Another object is to provide shingles which when laid up will present a thickened appearance at the butt with an equal number of layers of material at the lateral margins of the butt and at the portions thereof intermediate the margins, so that the margins of the butt end of the shingle will be in the same uniform plane with the intermediate portions, thereby eliminating the unsightly appearance due to sagging of the intermediate portions and the formation of ridge-like elevations at the laterally overlapped edges of the shingles.

Another object is to provide such shingles in a form in which they may be cut from a sheet of roofing material without waste.

In the drawings:

Figure 1 illustrates the form of shingle embodying the invention, and showing the nailing tab extended.

Figure 2 shows the appearance of several shingles in assembled position.

Figure 3 is a view similar to Figure 2, but showing the shingles arranged in a slightly different manner.

Figure 4 is a horizontal cross-section through line 4-4 of Figure 2.

Figure 5 illustrates the manner in which

the shingle elements may be cut from a sheet of roofing material without waste.

Figure 6 is a view showing shingles with a special form of nail receiving opening.

Referring in detail to the drawing, 10 represents the main body portion of the shingle element embodying the present invention. The shingle is of generally rectangular form, having vertical parallel side edges 11 and 12, and a horizontal upper edge 13. At its lower end the shingle is formed with the aligned edges 14 extending inwardly of the side edges 11 and 12. A nailing tab 15 projects forwardly of the edges 14 as shown. The nailing tab 15 may be of any desired configuration, the essential requisite, however, being that the maximum longitudinal dimension thereof does not exceed the distance which the elements are spaced apart in the horizontal courses when laid on the roof. As illustrated the nailing tab is preferably of elongated rectangular form, having parallel vertical side edges 16 extending at right angles to the edges 14, and a horizontal bottom edge 17, which is parallel to the edges 14.

As heretofore indicated, the nailing tab 15 is adapted to be underfolded into a position underlying the lower extremity of the main body portion of the shingle. The line along which the tab may be folded is preferably one connecting the inner ends of the two edges 14, and is indicated in the drawing at 18.

In certain instances it may be desirable to mark or impress the elements with painted or scored guide lines 20, at a suitable distance below the upper edge 13, in order to facilitate the proper spacing of the shingles of one horizontal row from those of the preceding horizontal row.

Shingle elements as thus described may be cut from a sheet of mineral surfaced roofing material without waste, as shown in Figure 5, where it will be seen that the cutting operation may be performed so as to produce two longitudinal rows of elements side by side, 100 with the nailing tab of the shingles of one row composed of the material cut away to form one of the edges 14 and 16 on each of a pair of adjoining units in the opposite row. Thus, I may employ a sheet of roofing material A, of suitable width, approximating

twice the vertical distance between the top edge of the shingle and a point midway of the nailing tab. In the operation of cutting the shingles as illustrated, there is formed 5 in the sheet a longitudinal series of transverse cuts 30, and a parallel series of similar cuts 30', staggered longitudinally with respect to the first named series to an extent equal to one-half the width of the shingle. 10 These transverse cuts define the side edges 11 and 12 of the shingles, as will be readily apparent. An intermediate series of transverse cuts 40, are made to define the edges 16 of adjoining shingles, and the complete separation of the units from the sheet may be effected by the staggered longitudinal cuts 50 alternately connecting adjacent ends of the cuts 40 and defining the bottom edges 17 of shingles in one row, and the edges 14 of the 15 adjoining pair of shingles in the other row. 20 It will be apparent that by means of suitable mechanism, the foregoing cutting operations may be carried on simultaneously and in a continuous manner. 25 The shingles may be laid either as shown in Figure 2 or in Figure 3. In either instance the units of each horizontal course are widely spaced from each other and are secured in place by the nailing devices 60 passing 30 through the tabs 15 at points adjacent the ends thereof, and by the nails 61 driven through the shingles along the margins, as shown. The shingles are laid so that the nailing tabs are disposed in the space between the opposed marginal edges of the 35 units in the preceding course and preferably with the edges 16 of the tabs abutting the marginal edges of the shingles in the preceding row, so as to properly align the shingles. 40 In the form illustrated in Figure 2 the vertical spacing of the successive courses is gauged by aligning the edges 17 of the retroverted nailing tabs with the upper edges 18 of the aligned shingles in the second lower 45 row. With this arrangement, a maximum portion of the entire area of the shingle is exposed to the weather. Where, however, it is not desired to expose such a large portion of each shingle, the successive courses may 50 be applied as shown in Figure 3, with the edges 17 positioned in alignment with the scored or printed gauge line 20 adjacent the upper ends of the underlying shingles in the second preceding row. 55 In Figure 6 I have shown an arrangement of shingles of the type already described but embodying as an additional feature, the employment of vertically elongated nail receiving holes 21 adjacent the ends of the nailing 60 tabs 15. Any suitable nailing device 60', in the form of a headed-fastener may be driven through the holes 21 to fasten the elements in place, the elongation of the holes allowing

the underlying structure to freely expand and contract without causing the shingles to 65 buckle.

From the foregoing description, numerous advantages will be apparent to those skilled in the art. Attention however, is particularly directed to the fact that the butt end 70 of the shingle presents a heavy appearance while the nailing tab enables the shingle of each course to be quickly and accurately spaced, and to the further fact that said tab is confined within the space between the marginal edges of the laterally adjacent shingles, being neither overlapped by, nor overlapping the latter. With such construction, each shingle lies snug and flat against the underlying shingles so as to prevent rain from 75 being driven sidewise under the side edges of the shingles or up under the butt thereof.

I claim as my invention:

1. A roof composed of overlapping courses 85 of rectangular shingles, the shingles of each course being substantially flat throughout their entire extent and laid with the side edges thereof vertical, and the adjacent shingles in each course being spaced from each other a distance greater than the distance 90 by which said adjacent shingles each overlap the underlying shingle in the previous course, each shingle having a retroverted nailing tab at its lower end, the ends 95 of said tab lying in abutment with the opposed vertical edges of the laterally adjacent shingles in the previous course.

2. A roof composed of overlapping courses 100 of rectangular shingles, the shingles of each course being substantially flat throughout their entire extent and laid with the side edges thereof vertical, and the adjacent shingles in each course being spaced from each other a distance greater than the distance by which 105 said adjacent shingles each overlap the underlying shingle in the previous course, each shingle having a retroverted nailing tab at its lower end, said tab lying wholly within the space between the opposed vertical edges 110 of laterally adjacent shingles in the previous course, and being neither overlapped by nor overlapping said shingles of the previous course.

3. A flexible roofing element comprising a 115 main body portion flat thruout its entire extent and of rectangular configuration, and a retrovertible tab projecting from one of the horizontal edges of the body portion, said tab being narrower than the body portion and being adapted to occupy the space between 120 the marginal edges of a pair of substantially adjacent elements of a preceding course, when said elements are laid widely spaced on a roof.

GERALD R. STARK.

CERTIFICATE OF CORRECTION.

Patent No. 1,698,032.

Granted January 8, 1929, to

GERALD R. STARK.

It is hereby certified that error appears in the printed specification of the above numbered patent requiring correction as follows: Page 2, line 116, claim 3, before the word "rectangular" insert the word "substantially" and line 121, strike out the word "substantially"; and that the said Letters Patent should be read with these corrections therein that the same may conform to the record of the case in the Patent Office.

Signed and sealed this 12th day of March, A. D. 1929.

(Seal)

M. J. Moore,
Acting Commissioner of Patents.
